UNITED STATES PATENT OFFICE.

EMIL E. GEIB, OF NEW YORK, N. Y.

PIPE-BOWL CLEANER.

Application filed April 17, 1923. Serial No. 553,524.

To all whom it may concern:

Be it known that I, EMIL E. GEIB, a citizen of the United States, residing at New York city, borough of the Bronx, in the county of Bronx and State of New York, have invented certain new and useful Improvements in Pipe-Bowl Cleaners, of which the following is a specification.

This invention relates to the class of tobacco and has particular reference to implements or devices for scraping the interior surface of a smoking pipe bowl.

Among the objects of the invention is to provide a small and efficient device of the character stated and one which may be made relatively cheap and which is adapted for convenient carrying in one's pocket, as at one end of a watch chain or the like. The device furthermore may partake of an ornamental significance and be suitably plated or otherwise decorated if desired.

The prime object of the invention however is to provide a pipe bowl cleaner having two correlated legs or blades, each designed to act as a resistance member for the other leg or blade when the instrument has imparted to it a rotating movement around the vertical axis of the bowl, one of the blades being formed with greater curvature or convexity than the other so that it will scrape thoroughly a pipe bowl having maximum concavity.

Another object of the invention is to provide a cleaning or scraping blade for a pipe bowl having a series or succession of chisel points directed downward, whereby when the instrument is given a reciprocating movement parallel to the axis of the bowl one or more of said chisel points will serve to positively and directly cut or loosen any accumulations of material from the inner surface of the bowl, and thus with a subsequent rotation of the instrument all such accumulations will be discharged.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings, in which like reference characters designate the same parts in the several views, and in which—

Figure 1 is an enlarged elevation of a

preferred form of the invention, a part being in section.

Fig. 2 is an edge view of the same.

Fig. 3 is a detail perspective view of the spring.

Fig. 4 is a horizontal section on the line 4—4 of Fig. 1.

Fig. 5 is a side elevation of a casing designed to carry the improved cleaner as a pocket piece.

Referring now more specifically to the drawings I show my improved pipe bowl cleaner as comprising two legs pivoted together scissor fashion at 10, each leg comprising a head 11, a shank 12, and a blade, one leg having a blade 13 and the other a blade 14.

Each head is wider than the adjacent connected shank portion forming shoulders 15.

The spring 16 I prefer to employ is bow shaped and has its ends slotted, forming a series of three fingers 17 and 18. The fingers 17 lie against the inner sides of the heads 11, while the fingers 18 formed in pairs are turned at an angle to the finger 17 and embrace the shanks 12 directly against the shoulders 15. Covering each head 11 is a cap 19 constituting a finger piece and a finish for the handle. Each cap extends well over the finger portions of the adjacent end of the spring and is crimped down around such parts as shown at 20, producing an effective interlock holding the spring in the place indicated and the cap from losing off of the head.

The blade 13 is shown provided with a series of teeth 21, preferably chisel shaped and directed downward so that with the reciprocation of the instrument up and down, parallel to the axis of the bowl into which either or both of the blades of the cleaner may be projected, at least one of the chisel points of the teeth will cut the material on the pipe bowl from the surface thereof, thoroughly cleansing the same. If the bowl is formed with maximum concavity the lowermost chisel points at least will engage every portion thereof while the instrument is moved from one end of the bowl to the other and also given a slow rotating movement around the axis of the bowl while the cutting action due to the reciprocations of the instrument is continued. This action of the chisel points or teeth may be resorted to

somewhat infrequently for the reason that the usual cleaning or scraping action may

be performed by the square sharp edge portions 22 of the blade 14. These edges will always engage sharply with the surface of the bowl due to the curvature as suggested by the dotted arc 23, Fig. 4. The chisel points may be slightly rounded as shown in this figure to increase the scraping action while being reciprocated.

The ends or points of the blades may have any suitable shape to project into and scrape the pit of the bowl, and they are preferably provided with relatively sharp knife edges 24. These ends of the blades will strike against each other to limit the swing of the blades toward each other and thereby the spring, whose function is to separate the blades, will not be over strained.

In practice for ordinary cleansing or scraping of the bowl the instrument is plunged directly into the bowl with the handles extended above the bowl in position to be rotated or twisted around the axis of the bowl. The depth to which the instrument is projected into the bowl will depend upon the depth of the bowl and its interior shape, but in most instances the blades will accommodate themselves directly to various sizes and shapes of bowls, the spring acting at all times to cause both blades to engage against opposite sides of the bowl, whereby each blade is a resistance for the other. If the accumulations are persistent they may be dislodged by imparting a reciprocating movement to the instrument as already set forth.

The device is designed in a neat and convenient form so as to be carried in a relatively small shell or casing 25 and suspended

from a watch chain by a ring 26, or otherwise carried in one's pocket as a pocket piece.

I claim:

1. In a pipe bowl cleaner, an abrading member arranged for action with its axis approximately parallel to the axis of the bowl and having a rounded cutting chisel edge lying in a plane transverse to said axis.

2. In a pipe bowl cleaner, the combination of a pair of oppositely arranged scraping blades movable toward and from each other, and a spring acting upon the blades to cause them to separate and thereby hug the opposite sides of the bowl, said spring having slotted ends, and means embracing said ends to hold the spring in position.

3. In a pipe bowl cleaner, the combination of two relatively movable scraping members pivoted together and having finger pieces at their outer ends, said finger pieces comprising caps slipped over the ends of the members, and a leaf spring located between the members and having its ends slotted to embrace the members while said ends are embraced by the finger pieces and thereby held in position.

4. A device as set forth in claim 3 in which the ends of the scraping members are provided with shoulders and the ends of the spring are slotted to form fingers embracing the ends and abutting against said shoulders, and the finger pieces extended over the slotted ends of the spring to hold the same against said shoulders and prevent the finger pieces from accidental removal.

In testimony whereof I affix my signature.
EMIL E. GEIB.
